APPARATUS FOR HANDLING MATERIAL

Application filed May 9, 1929. Serial No. 361,597.

This invention relates to apparatus for handling materials, and aims to facilitate the movement, and more particularly the treatment, of materials.

5 The invention relates to apparatus of the type described and claimed in Baker Patent No. 1,672,404, in which a number of wheeled collapsible carriers, each provided with a number of carrying elements, are moved in a 10 closed circuit in such manner as to place the carrying elements in edge-to-edge relation at a loading station, in superimposed relation in a treatment space, and in a vertical position at a dumping station.

15 Each carrier shown in said patent was provided with three pairs of wheels of three different gauges so arranged that the relation of these three pairs of wheels controlled the position and relation of the carrying elements of the carrier. In my co-pending application, Serial No. 361,383 filed May 8, 1929, I have described an improved handling apparatus providing, for such carriers, a track circuit in a vertical plane, including three substantially continuous tracks of different gauges for the three pairs of wheels of the carriers.

20 The object of my present invention is further to simplify such handling apparatus. In accordance with the invention, this is accomplished by making the two upper pairs of wheels of each carrier of the same gauge and providing a closed track circuit in a vertical plane including only two tracks. One 25 of these tracks supports the two upper pairs of wheels of the carrier, and is provided with branches and switches which permit moving these two pairs of wheels in separate paths where necessary.

25 Other objects and advantages of the invention are hereinafter described in connection with a detailed description of a practical embodiment of the invention shown in the accompanying drawings, in which:

Fig. 1 is a diagrammatic plan view of a 30 fragment of the track circuit for the carriers;

Fig. 2 is a diagrammatic side elevation of the entire track circuit indicating different positions taken by a carrier in passing around the circuit;

35 Fig. 3 is a diagrammatic side elevation of

a system of chain conveyors which may be utilized to move the carriers around the track circuit shown in Fig. 2;

Fig. 4 is a side elevation of the rails of the track circuit shown in Fig. 2, looking outwardly from the middle of the apparatus and showing parts of the rails broken away;

Fig. 5 is a fragmentary plan view of one of the switches and the rails associated therewith, omitting parts shown in line 5-5 of Fig. 4;

Fig. 6 is a side elevation of one of the switches and the parts of the rails near it; and

Fig. 7 is a plan view of one of the carriers in loading position.

The apparatus illustrated includes a large number of collapsible carriers 10, each provided with a plurality of carrying elements such as trays 20, and means for moving these carriers in a closed circuit which takes each tray past a loading station L, through a treatment space T, to a dumping station D, and back to the loading station L.

70 The carriers 10, like those shown in Baker Patent No. 1,672,404, consist essentially of carrying elements or trays and connecting members hinged together in parallelogram arrangement. The construction of a carrier 10 is best shown in Fig. 7. The carrier has a connecting member 11 consisting of rigid side bars 12, 12', joined by tie rods 13, and a connecting member 14 consisting of side bars 15, 15', joined by tie rods 16. A number of trays 20 are hinged to the connecting members 11, 14. Each tray, except the upper one 20a, has on its bottom two spaced cross bars 21 which are pivoted on the tie rods 13, 16 of the connecting members. The upper tray has side-pieces 22 rigidly secured to it, and hinged to the upper ends of the side bars 12, 12' of the connecting member 11 by pivots 13', and to the upper ends of the side bars 15, 15' of the connecting member 14, by pivot rods 16'. The distance between

80 the adjacent pivot of each connecting member is equal to the length l of one of the trays 20, so that the trays may be brought into edge-to-edge relation in a common plane by bringing the connecting members together.

85 90 95 100

Each tray is provided at one edge with a lip 23 which overlaps the adjacent edge of the next tray when the trays are in edge-to-edge relation. The upper tray has a lip 24 at its other edge to overlap the lip 22 of the lowest tray 20b at the loading station (Fig. 7).

Each carrier is provided with three pairs of wheels A, B and C. The wheels A are co-axial with the hinge pivots 16' which connect one of the carrying elements, 20a, and one of the connecting members, 14. The wheels B are secured on this carrying element 20a at a distance from the wheels A, and the wheels C are mounted on this connecting member 14 at a distance from the wheels A. The wheels C may be mounted on the lowest of the rods 16 as shown. The wheels B may be co-axial with the pivots 13' but, because of the provision of the rigid side-pieces 22 on the upper tray 20a, may be placed further from the axis of the wheels A, as shown, to give greater stability to the carrier.

To provide for engagement of the carriers by the flights of chain conveyors, the wheels A have projecting axles A' extending over the chains of a wide-gauge conveyor 50, indicated by dot and dash lines in Fig. 7 and hereinafter described; and the wheels C have projecting axles C' extending over the chains of a narrow-gauge conveyor 60, indicated by dot and dash lines in Fig. 7 and hereinafter described. The side-pieces 22 are cut away to expose the axles B' of the wheels B to the flights of the conveyor 60 and contain grooves 25 to permit the flights to reach these axles without interference.

The relative position of the pairs of wheels A, B and C determines the position of the trays 20 and their relation to each other. The pairs of wheels A and B are of the same gauge, while the pairs of wheels C are of a narrower gauge. A track a is provided for supporting the wheels A and B, and a track c of a narrower gauge is provided for supporting the wheels C.

The arrangement of the two tracks may best be understood from the diagrammatic views, Figs. 1 and 2. Fig. 1 serves merely to indicate two different kinds of lines by which the wide-gauge track a and the narrow-gauge track c may be identified in the side elevation, Fig. 2. The track a is indicated by a dash line, track c by a dot line, and a dot and dash line is used in the side elevation to indicate the portions of the tracks a and c which are coplanar.

From Fig. 2, it will be seen that at the loading station L, the two tracks are horizontal and in the same plane, being represented by the line ac1. Beyond the loading station, the track a has a horizontal portion a2, while the track c has a downwardly inclined portion c2 at the entrance to the treatment space T and a horizontal portion c3

below the level of the portion a2 of the track a and separated from this portion of the track a by a vertical distance less than the length of a connecting member of one of the carriers. In the lower part of the treatment space, the tracks a and c have horizontal portions a4, c4, separated by the same vertical distance. The right-hand ends of the upper and lower horizontal portions a2, a4 of the track a are connected by two parallel inclined and curved branches a5, a5' which are separated by a horizontal distance equal to the distance between the pairs of wheels A and B. The outer branch a5' is connected to the end of the upper portion a2 by a switch a6 and directly joins the end of the lower portion a4, while the inner branch a5 directly joins the end of the upper portion a2 and is connected by a switch a7 to a point of the lower portion a4 at a little distance from its end. The upper and lower horizontal portions c3, c4 of the track c are connected by an inclined portion c5 which contains a switch c6 at the point at which it crosses the track a and a switch c7 at the point at which it joins the horizontal portion c4.

At the dumping station D, the track a has an upwardly inclined portion a8, two branches a9, a9', followed by a curved portion a10, and a horizontal portion a11 joining the horizontal portion represented by the line ac1 at the loading station. On approaching the dumping station, the track c has an upwardly inclined portion c8, bringing it to the level of the lower horizontal portion a4 of the track a. The portion c8 of the track c lies in the same inclined plane as the portion a8 of the track a. The track c then crosses the track a having a more steeply inclined portion c9 curving into a horizontal portion c10 and an oppositely inclined portion c11 bringing it up to join the portion of the track c at the loading station, which is on a level with the track a and is represented by the line ac1. The track c is provided with a switch c12 at the point at which it crosses the track a and with a switch c13 where its incline c11 joins its horizontal portion c10.

The branch a9' of the track a extends on a line with the inclined portion a8 of the track, but is separated from the end of the portion a8 by a break a12, and from the end of the curved portion a10 by a break a13 bridged by a switch a14. The branch a9 is directly connected to the ends of the portions a8 and a10 of the track a. This branch has a downwardly inclined portion a9¹, bringing it to a pocket a9² which is below the break a12 and at a distance from it equal to the distance between the pairs of wheels A and B. Beyond the pocket a9² is a bump a9³ and an upwardly inclined portion a9⁴ which joins the end of the portion a10 of the track.

The positions which each carrier assumes in traveling around the circuit are indicated

diagrammatically in Fig. 2 at 10a, 10b, etc. The diagrammatic indication of the carrier shows merely the position of its wheels A, B and C, of its upper tray 20a, and of its connecting member 14. It will be understood from the description of the carrier previously given, that all the trays of the carrier are at all times parallel to its upper tray 20a, and that its other connecting member 11 is at all times parallel to its connecting member 14.

In the loading position indicated at 10a, the three pairs of wheels of the carrier are supported on the same level, so that the trays of the carriers are in edge-to-edge relation in a common plane. As the carrier proceeds to the right and enters the treatment space, its wheels C run down the incline c2 as shown at 10b, so that, when the carrier has entered the treatment space as shown at 10c, its connecting members are inclined and its trays are horizontal and in stepped relation.

When the carrier reaches the right-hand end of the treatment space, its wheels C descend along the incline c5; and its wheels A cross the switch a6, which is then automatically opened, so as to permit the wheels B to descend along the branch a5, while the wheels A descend along the parallel branch a5'. As these branches are separated by a horizontal distance equal to the distance between the wheels A and B and are substantially parallel to the incline c5, the trays of the carrier are maintained in horizontal position and in stepped relation during its descent. During the descent of the carrier, the switch c6 is automatically closed by the wheels C as they cross it and automatically re-opened to permit the axles of the wheels A and B to pass through it, the switch a7 is opened by the wheels A after the wheels B have passed over it, and the switch c7 is closed by the wheels C, and automatically re-opened.

After the carrier has passed to the left through the lower part of the treatment space with its trays in stepped relation, its wheels A and B mount the incline a8 while its wheels C mount the incline c8 bringing the trays of the carrier into edge-to-edge relation in a plane slightly inclined to the horizontal. When the wheels B of the carrier reach the break a12 at the end of the portion a8 of the track a, they drop down along the incline a9¹ of the branch a9 into the pocket a9². While the wheels B remain in this pocket, the wheels A may be moved across the break a12 onto the branch a9', being supported in this movement by the upper tray 20a and its rigid side members 22 which pivot around the axis of the wheels B. As the wheels A proceed up the branch a9', the wheels B remain in the pocket a9² until they are pulled over the bump a9³. The wheels A cross the switch a13 to the curved portion a10 of the track a while the wheels B follow along the branch a9 and open the switch a13 to reach the curve a10 of the

track after the wheels A. The dropping of the wheels B into the pocket a9² brings the trays of the carrier into a substantially vertical position, and the trays are slightly inverted and jounced as the wheels B are drawn over the bump a9³ so that they are completely emptied at the dumping station. While the wheels A have been mounting the incline a8, a9' and passing around the curve a10, the wheels C have closed and crossed the switch c12 and been moved up the steep incline c9 under, and then over, the switch c13, and then up the incline c11, so that all three pairs of wheels are brought back to a common level at the loading station L.

The rails of the tracks a and c may be conveniently formed of angle irons, although other forms of rails may be used. Channel irons 29 and crescent-shaped members 30 may be conveniently used for the rails of the branches a5, a5' and the track a as shown in Fig. 4.

The construction of the automatic switches contained in the track circuit is shown in Figs. 4, 5 and 6. The switches, a7, c13 and a14, which are normally closed, consist of simple pivoted arms which may be raised by wheels passing under them. The switch c7 consists of pivoted arms provided with counterweights 31 to hold them normally open. The switch c6 consists of pivoted arms also provided with counter weights 32 to hold them normally open, and pivoted tappet levers 33 are provided below this switch to insure its being thrown open by the wheels C after they have crossed them.

The switch c12 consists of arms pivoted to the upper ends of the rails of the portion c8 of the track c and provided with stops 34 which normally hold them in a horizontal position overlapping the upper part of the portion c8 of the track c, so that the wheels C may enter under them and tip them up. To insure immediate opening of the switch c12 after the wheels C have crossed it, counterweights 35 are pivoted on the pivots 36 of the switch arms and provided with stops 37 to engage the switch arms as soon as these arms are moved to a vertical position by the wheels C. Further movement of the switch arms by the wheels C swings the counterweights 35 up and to the right, so that the counterweights act to throw the arms open as soon as the arms are released by the wheels C.

The switch a6 is formed by two tilt tables 38 and 39 associated with each rail of the track a. Their fulcrums 40 and 41 are separated by the same distance as that between the axes of the pairs of wheels A and B. A link 42 connecting arms 43, 44, secured to the two tables, prevents them from tilting independently of each other. A stop 45 is provided under the inner end of the table 38, and a stop 46 under the outer end of the

table 39. When the wheels A and B of a carrier reach the right-hand end of the horizontal portion a_6 of the track a , the wheels B move onto the inner arm of the table 38 before the wheels A cross the fulcrum point of this table. The table 38 is thus held horizontal until the wheels A pass off its outer arm onto the inner arm of the table 39. While the wheels A are on the inner arm of the table 39 and the wheels B are on the inner arm of the table 38, the tables are held horizontal by the stop 45, but, as soon as the wheels cross the fulcrums of the two tables, both tables tip until the table 39 encounters the stop 46, so that the wheels B are directed to the branch a_5 , while the wheels A are directed to the branch a_5' . To prevent premature tipping of the tables in case the weight is unevenly distributed between the wheels A and B, a guard rail 47 is provided above the tables to engage the upper sides of the wheels A and B and positively to prevent any tipping of the tables before the wheels reach their fulcrums.

Automatic movement of the carriers 10 along the tracks may be secured by interconnected conveyors operating in timed relation. The track arrangement which has been described permits the use of a very simple conveyor arrangement, which is shown diagrammatically in Fig. 3. Only three conveyors are used, of which two, 50 and 60, operate at a relatively high speed for transferring the carriers between the upper and lower levels, while the third, 70, operates at a relatively low speed to move the carriers in both directions along the horizontal parts of the circuit. Each conveyor may consist of two chains having reaches lying close to a portion of one of the tracks, and provided with flights for engaging a part of the carriers 10. The chains of the conveyor 70 are positioned, as indicated by dot and dash lines in Fig. 7, so that their flights may engage the projecting axles C' of the wheels C and the axles B' of the wheels B inside the wheels. The chains of the conveyor 60 are positioned, as indicated by dot and dash lines in Fig. 7, so that their flights may engage the projecting axles A' of the wheels A. The chains of the conveyor 50 are of the same separation as those of the conveyor 60.

From the partial indication of the tracks in Fig. 3, the relation between the conveyors shown in Fig. 3 and the track circuit shown in Fig. 2 is apparent: To enable the conveyor 50 to transfer the carriers from the upper tracks to the lower tracks at the right-hand end of the treatment space, the chains of this conveyor follow the course of the track a at the right-hand end of its horizontal portion a_2 and along its branch a_5' . To enable the conveyor 60 to transfer the carriers from the lower tracks to the upper tracks at the left-hand end of the apparatus and to

move them past the loading station, the chains of this conveyor follow the course of the track a at the left-hand end of its horizontal portion a_4 , at its inclined portion a_8 , at its branch a_9' , at its curved portion a_{10} , at its horizontal portion a_{11} , a_{12} , and at the left-hand portion of its horizontal portion a_2 . To enable the conveyor 70 to move the carriers to the right in the upper part of the treatment space and to the left in the lower part, its chains have upper reaches following the course of the horizontal portion c_3 of the track c and lower reaches following the course of the horizontal portion a_4 of the track a .

The speed of the conveyors is so related that the trays of the carriers are moved past the loading station closely spaced in single file and through the treatment space closely spaced in multiple file. For this purpose, the speed of the conveyor 60, which moves the carriers past the loading station, is substantially equal to the speed of the conveyor 70 multiplied by the number of trays in each carrier. The speed of the conveyor 50 is preferably somewhat greater than that of the conveyor 60. In order that each carrier may be positively guided and timed throughout its circuit, the flights of the different conveyors are spaced apart by distances proportional to the speed of the conveyors.

Various forms of known mechanism may be used to operate the conveyors at the relative speeds specified. A mechanism suitable for this purpose is illustrated and described in my co-pending application, Serial No. 361,383 filed May 8, 1929.

Any desired or convenient form of mechanism may be provided for placing the material to be treated on the trays of the carriers at the loading station L, and for removing the material deposited from the trays at the dumping station D.

What I claim is:

1. The combination with a carrier having a plurality of carrying elements and connecting members hinged together in parallelogram arrangement and provided with two pairs of wheels of the same gauge and a third pair of wheels of a different gauge whose relation to the first two pairs of wheels controls the relation of the carrying elements of the carrier, of a closed track circuit in a vertical plane, comprising two substantially continuous tracks of different gauges differently spaced from one another about said circuit so as to cause the carrying elements of the carrier to assume successively an edge-to-edge loading position and a superimposed treatment position as the carrier is moved around the circuit.

2. The combination with a carrier having two pairs of wheels of the same gauge, of a closed loop of track in a vertical plane having two double portions consisting of

branches separated by a distance equal to that between the two pairs of wheels, and automatic means for causing the two pairs of wheels to follow different branches at the 5 double portions of the track so as to cause two reversals of the relative position of the pairs of wheels as they pass around the loop of track.

3. The combination with a carrier having 10 two pairs of wheels of the same gauge, of upper and lower tracks for said wheels, a fixed inclined track connecting one end of the upper track with the lower track, a fixed parallel inclined connecting track spaced 15 outwardly from the end of the upper track, a switch normally bridging the space between the end of the upper track and said second inclined track, and means for automatically opening said switch when the two pairs of 20 wheels of the carrier are located respectively over the upper ends of said two inclined tracks.

4. The combination with a carrier having a plurality of carrying elements and connecting members hinged together in parallelogram arrangement and provided with two upper pairs of wheels of the same gauge and a lower pair of wheels of a different gauge, of a track for the upper wheels consisting of 25 30 upper and lower horizontal parts, an inclined part connecting one end of the upper part with the lower part, a parallel inclined part spaced outwardly from the end of the upper part, a switch normally bridging the space 35 between the end of the upper part and said outer inclined part, and means for automatically opening said switch when the two upper pairs of wheels of the carrier are located respectively over the upper ends of said two 40 inclined parts, and a track for the lower pair of wheels consisting of an upper part, a lower part and an inclined part, located at substantially uniform distances below the corresponding parts of the track for the upper 45 wheels.

5. The combination with a carrier having two pairs of wheels of the same gauge, of upper and lower horizontal tracks for said wheels, a double inclined and curved connecting track consisting of two fixed parallel branches separated by a horizontal distance equal to the distance between the two pairs of wheels, a switch connecting one end of the outer branch to one of the horizontal tracks, 50 55 and a switch connecting the other end of the inner branch to an intermediate point of the other horizontal track.

6. The combination with a carrier having two pairs of wheels of the same gauge, of a 60 horizontal track, an inclined track extending from one end of said horizontal track, a parallel inclined track spaced outwardly from the end of the horizontal track by a distance equal to that between the two pairs of wheels, 65 a pair of tilt tables fulcrumed at the upper

ends of said inclined tracks, and means connecting said levers so that neither one can tip without tipping the other.

7. The combination with a carrier having two pairs of wheels of the same gauge, of a track for said wheels containing two breaks, a loop of track of the same gauge below said first track connecting the ends of the portions of said first track at the outer sides of said breaks and having a pocket at a distance 70 75 from the first break substantially equal to the distance between the two pairs of wheels of the carrier, and an upwardly opening switch bridging the other break in the first track.

8. The combination with a carrier having two pairs of wheels of the same gauge, of a track for said wheels containing two breaks, a loop of track of the same gauge below said first track connecting the ends of the portions 80 85 of said first track at the outer sides of said breaks and having a pocket at a distance from the first break substantially equal to the distance between the two pairs of wheels of the carrier, and a conveyor chain having a 90 reach extending parallel to said first track, and provided with flights to engage the carrier at the axis of one pair of its wheels.

In testimony whereof I have hereunto set my hand.

DAVID S. BAKER.
